UNITED STATES PATENT OFFICE

ROY H. ANDERSON, OF LONG BEACH, CALIFORNIA

PITCH SHACKLE

Application filed September 7, 1927. Serial No. 217,966.

The invention relates to improvements in shackles, commonly termed pitch shackles, used for connecting steam shovel buckets with the carrying legs thereof. The shackle 5 commonly used is formed with bolt receiving openings at its ends, and bolts pass through these openings and through apertured lugs on the leg and bucket, but in short time, the openings become so enlarged in the link that a great deal of lost play is permitted, accompanied by noise which it is desirable to prevent.

It is the object of my invention to provide a new and improved shackle provided with novel means for tightly holding the bolts against lateral play in the bolt receiving openings at the ends of said shackle, the construction being such that all wear may be effectively taken up.

With the foregoing in view, the invention resides in the novel subject matter herein-after described and claimed, the description being supplemented by the accompanying drawing.

Fig. 1 is a side elevation showing the application of the shackle.

Fig. 2 is a central vertical longitudinal sectional view through the shackle, parts being in elevation.

Fig. 3 is a horizontal sectional view on the line 3—3 of Fig. 2.

Fig. 4 is a perspective view of the bolt holding plungers and the operating wedge therefor.

The drawing above briefly described, illustrates the preferred form of construction and while this construction will be herein specifically explained, it is to be understood that within the scope of the invention as claimed, variations may be made.

The numeral 5 in the drawing denotes the improved shackle, said shackle being of the usual elongation and being longitudinally hollow. At its ends, this shackle is formed with spaced, longitudinally extending parallel lugs in which are formed transverse openings 6 to receive the usual pins or bolts 7 for connecting the shackle with the lugs 8 on the bucket 9 and the leg 10. Slidably mounted within the shackle 5, are two bolt holding

members 11 preferably in the form of metal blocks as shown, the outer ends of these blocks being adapted to abut the bolts 7 to hold the latter tightly in the openings 6. The inner ends of these blocks are in contact with opposite edges of a wedge 12 which passes slidably through a transverse opening 13—13 in the shackle 5. The small end of this wedge is provided with a threaded stud 14 upon which a nut 15 and washer 16 are disposed, said nut and washer engaging the exterior of the shackle. Thus, upon tightening of the nut 15, the wedge 12 is drawn inwardly, thereby causing it to force the blocks 11 tightly against the bolts 7, thus effectively holding the latter against lateral play.

As above stated, excellent results are obtainable from the details disclosed and they are therefore preferably followed. However, the present disclosure is to be considered as illustrative rather than limiting.

I claim:

1. An improvement in a steam shovel of the type having a leg, a bucket connected at its lower rear portion with the front end of said leg, a rearwardly projecting bifurcated lug on the upper end of the bucket, an upwardly projecting bifurcated lug on the front end of said leg spaced behind the first named lug, a pitch shackle whose ends are received between the furcations of said lugs, and transverse pins passing through said lugs and shackle ends; said improvement comprising a longitudinal recess in said shackle, blocks slidable in the ends of said recess and abutting said pins to tightly bind them in the pin-receiving openings of the shackle, and means for positively forcing said blocks outwardly.

2. An improvement in a steam shovel of the type having a leg, a bucket connected at its lower rear portion with the front end of said leg, a rearwardly projecting bifurcated lug on the upper end of the bucket, an upwardly projecting bifurcated lug on the front end of said leg spaced behind the first named lug, a pitch shackle whose ends are received between the furcations of said lugs, and transverse pins passing through

said lugs and shackle ends; said improvement comprising a longitudinal recess in said shackle, a transverse recess in the shackle intersecting said longitudinal recess, blocks 5 slideable in the ends of said longitudinal recess and abutting said pins to tightly bind them in the pin receiving openings of the shackle, a wedge in said transverse recess abutting the inner ends of said blocks, and 10 threaded tightening means for said wedge.

3. A pitch shackle comprising a hollow body having on each of its ends a pair of laterally spaced, longitudinally extending parallel lugs in which are formed alined 15 transverse bolt-receiving openings, the central portion of said body being formed with a tapered, transverse wedge-receiving opening, two solid flat-sided bolt-engaging blocks slidably mounted in the body of the shackle 20 between the bolt-receiving and wedge-receiving openings, a wedge in said wedge-receiving opening contacting with said blocks to force them against the bolts in said bolt-receiving openings, thereby tightly holding the 25 bolts in said bolt-receiving openings, and means for tightening said wedge.

In testimony whereof I have hereunto affixed my signature.

ROY H. ANDERSON.
